LIGHTING PANELING

Elmer Szantay, 735 S. Karlov Ave., Chicago, Ill.

Filed Apr. 18, 1961, Ser. No. 64,806

Term of patent 14 years

(Cl. D48—16)

Fig. 6.

FIG. 1 is a plan view of a portion of a lighting paneling showing my new design.

FIG. 2 is an enlarged fragmentary plan view of the paneling illustrated in FIG. 1.

FIG. 3 is a sectional view taken along the line 3—3 of FIG. 2.

FIG. 4 is a sectional view taken along the line 4—4 of FIG. 2.

FIG. 5 is a sectional view taken along the line 5—5 of FIG. 2.

FIG. 6 is a perspective view looking from the bottom of FIG. 2.

The design is repeated horizontally and vertically.

I claim:

The ornamental design for a lighting paneling, as shown and described.
